UNITED STATES PATENT OFFICE.

EDWARD D. MORRIS, OF CHICAGO, ILLINOIS.

SEAM PRESSER FOR SHOE UPPERS.

Application filed September 24, 1921. Serial No. 502,953.

To all whom it may concern:

Be it known that I, EDWARD D. MORRIS, a citizen of the United States, and a resident of the city of Chicago, county of Cook, and 5 State of Illinois, have invented certain new and useful Improvements in Seam Pressers for Shoe Uppers, of which the following is a specification.

This invention relates to seam pressers for 10 shoe uppers, and has for its object the provision of a device of this character adapted to press seams of varying thickness neatly and expeditiously.

Other objects will appear hereinafter.

15 The invention consists in the combinations and arrangements of parts hereinafter described and claimed.

The invention will be best understood by reference to the accompanying drawings 20 forming a part of this specification, and in which,

Fig. 1 is a side elevation of the invention;

Fig. 2 is a detail view of the invention partly in section, showing the mounting of 25 the pressing rollers;

Fig. 3 is a top plan view of the invention showing the swinging arm thereof in dotted lines in inoperative position;

Fig. 4 is a section on line 4—4 of Fig. 3; 30 and

Fig. 5 is a sectional view on the line 5—5 of Fig. 3.

The invention consists of a supporting table 1 of any suitable kind. Mounted on 35 the table 1 is a base member in the form of a casting 2 of any suitable material, and in said casting there is preferably provided a groove 3 adapted to snugly accommodate an arm 4 which is swingingly mounted on the rear end of said casting 2 by means of a pin 5 transfixing projecting lugs 6 on said casting as shown in Fig. 1. The arm 4 is normally resiliently urged to inoperative position by means of a tension spring 7 suitably 40 secured to the arm 4 at one end and having its opposite end secured to an extension 9 on the casting 2. The arm 4 is adapted to fit snugly in the groove 3 in the casting 2 to hold same rigid when in operative position,

50 and is retained in such position by means of a spring held latch 10 which is adapted to be retracted by pressure on the foot treadle 10' to permit the outward swinging of the arm 4. The arm 4 preferably supports at 55 its outer end a housing 11 of any suitable kind in which is journaled a shaft 12 carry-

ing a roller 13, such roller having its ends beveled as shown in Fig. 5.

Disposed above the arm 4 and mounted on the casting 2 in any suitable manner is an arm 14, which may be braced by a suitable framework if desired, a portion of a brace 15 being shown, which may be fastened in any suitable manner. Mounted in any suitable manner on the outer end of the arm 14 60 preferably above the housing 11 is a housing 16 provided with slots 16' in its sides. Loosely disposed but snugly fitting within the housing 16 is a second housing 17 which has a shaft 18, carrying a beveled roller 18', 65 journaled in its opposite side walls, the ends of such shaft projecting through the slots 16' in the housing 16. Threaded into the top wall of the housing 16 is a bolt 19, the smooth inner end of said bolt loosely projecting through the top wall of the inner housing 17 and being held in such position by a flange 20 thereon. Mounted between the inner surface of the top wall of the housing 16 and the outer surface of the top wall 70 of the housing 17 in any suitable manner are compression springs 21 which normally urge the housing 17 and the roller 18' toward the roller 13. By adjusting the threaded bolt 19, the clearance between the rollers 18' and 13 75 may be regulated according to the thickness of the seam to be operated upon and the amount of pressure it is desired to use in 80 pressing such seam.

The shaft 18 carrying the roller 18' has mounted at one end a pinion 22 which meshes with a driving worm 23 mounted on the outer end of a drive shaft 24 journaled in brackets 25 mounted on the arm 14, the opposite end of said shaft 24 having a pulley 26 keyed thereon adapted to be connected by a suitable means to a power pulley. Both the pinion 22 and worm 23 are provided with exceptionally deep threads so that they will remain meshed and operative 90 regardless of the limited movement of the pinion 22 and shaft 18 with the housing 17 when an adjustment is made to the pressing rollers.

In operation, the desirable pressure on the roller 18' is obtained by rotating the screw bolt 19. Shoe uppers are then manually presented between such rollers to press the seams thereof, each successive upper passing through the rollers, sliding its predecessor 105 forward along the arm 4 until the entire length of the arm is occupied, when by pres-

sure on the foot treadle the arm 4 will automatically swing outwardly due to the tension exerted by the spring 7 and the pressed uppers disengaged from the arm 4 over the 5 roller 13. The seam of a boot may also be pressed as above described, the arm 4 supporting same during the operation. By the employment of my apparatus, the seams of shoe uppers or boots may be properly 10 pressed during any stage of the construction thereof economically and expeditiously.

While I have illustrated and described the preferred form of construction for carrying my invention into effect, this is capable of 15 variation and modification without departing from the spirit of the invention. I, therefore, do not wish to be limited to the precise details of the construction set forth, but desire to avail myself of such variations 20 and modifications as come within the scope of the appended claims.

Having described my invention, what I claim as new and desire to secure by Letters Patent is:

25 1. A seam presser of the character described comprising a base member having a laterally opening groove; and a swinging arm adapted to swing into and snugly engage said groove and be rigidly supported 30 against vertical movement.

2. In a seam presser of the character described comprising a base member having a laterally opening groove; a swinging arm adapted to snugly engage said groove and 35 be rigidly supported against vertical movement; a presser roller carried by said arm; another presser roller mounted adjacent to and cooperating with said first mentioned presser roller; and means for adjusting the 40 pressure exerted by said rollers.

3. In a seam presser of the character described comprising a base member having a laterally opening groove; a swinging arm hinged on said base member and snugly engaging said groove and supported against 45 vertical movement; means normally urging said arm to inoperative position; and means for retaining said arm in operative position.

4. In a seam presser of the character described comprising a base member having a laterally opening groove; an arm pivoted beyond said groove and adapted to swing thereinto and be supported against vertical movement; a lateral projection on said arm 55 adjacent said pivot; and a spring connected to said projection and said arm normally urging said arm to inoperative position.

5. In a seam presser of the character described comprising a base member having a laterally opening groove; an arm pivoted beyond said groove and adapted to swing thereinto and be supported against vertical movement; a lateral projection on said arm adjacent said pivot; a spring connected to 60 said projection and said arm normally urg-

ing said arm to inoperative position; a catch for holding said arm in operative position; and means for releasing said catch.

6. In a seam presser of the character described comprising a base member having a laterally opening groove; a swinging arm hinged on said base member and snugly engaging said groove; means normally urging said arm to inoperative position; means for retaining said arm in operative position; a presser roller mounted in the end of said arm; and an adjustable presser roller mounted above said first-named presser roller and co-operating therewith.

7. In a seam presser of the character described comprising a support; telescopic housings mounted on said support; a presser roller mounted in the inner of said housings; a laterally swinging arm mounted adjacent said support and having a corresponding presser roller co-operating with said first-named presser roller; and resilient means engaging said inner housing for pressing the roller therein toward the presser roller mounted in said swinging arm.

8. In a seam presser of the character described comprising a support; telescopic housings mounted on said support; a presser roller mounted in the inner of said housings; a base member disposed adjacent said support having a laterally opening groove; a swinging arm carrying a pressing roller adapted to co-operate with said first-named pressing roller, said arm being adapted to swing into said groove and be supported thereby; and means engaging said inner housing for resiliently holding said first named roller in position.

9. In a seam presser of the character described comprising a support; telescopic housings mounted on said support; a shaft mounted in the inner of said housings and slidably mounted in the outer of said housings; a presser roller mounted on said shaft in the inner of said housings; an adjusting screw threaded into said outer housing and having its inner end slidably secured to said inner housing; resilient means mounted between the outer surface of said inner housing and the inner surface of said outer housing; and driving means connected to the outer end of said shaft.

10. In a seam presser of the character described comprising a support; telescopic housings mounted on said support; a shaft mounted in the inner of said housings and slidably mounted in the outer of said housings; a presser roller mounted on said shaft in the inner of said housings; an adjusting screw threaded into said outer housing and having its inner end slidably secured to said inner housing; resilient means mounted between the outer surface of said inner housing and the inner surface of said outer housing; a pinion on one end of said shaft; and

driving means engaging said pinion and adapted to remain in operative engagement therewith despite movement of said shaft.

11. A seam presser of the character described comprising a base member having a groove open at one side; and an arm adapted to swing into and snugly engage said groove and be rigidly supported against movement in all directions except toward

10 the open side.

12. A seam presser of the character described comprising a base member having a groove open at one side; an arm adapted to swing into and snugly engage said groove and be rigidly supported against movement in all directions except toward the open side; and removable means for preventing movement of said arm toward said open side.

20 13. A seam presser of the character described; a base member having a groove open at one side; a supporting member disposed adjacent to said base member and having a presser roller mounted thereon; and an arm having a presser roller thereon adapted to swing into and snugly engage

said groove, the swinging of said arm into said groove causing said presser rollers to assume operative relation with respect to each other.

14. A seam presser of the character described; a base member having a groove open at one side; a supporting member disposed adjacent to said base member and having a presser roller mounted thereon; an arm having a presser roller thereon adapted to swing into and snugly engage said groove, the swinging of said arm into said groove causing said presser rollers to assume operative relation with respect to each other; means normally urging said arm out of engagement with said groove; and a spring catch for holding said arm in said groove.

In testimony whereof I have signed my 45 name to this specification in the presence of two subscribing witnesses.

EDWARD D. MORRIS.
